UNITED STATES PATENT OFFICE.

DAVID FRANKLIN YOUNGBLOOD, OF SAN ANTONIO, TEXAS.

DOOR-OPERATING MEANS.

1,030,699.

Specification of Letters Patent. Patented June 25, 1912.

Application filed November 8, 1911. Serial No. 659,199.

To all whom it may concern:

Be it known that I, DAVID F. YOUNGBLOOD, a citizen of the United States, residing at San Antonio, in the county of Bexar 5 and State of Texas, have invented a new and useful Door-Operating Means, of which the following is a specification.

The invention relates to improvements in mechanism for operating jail doors.

10 The object of the present invention is to improve the construction of mechanism for operating jail doors, and to provide simple, strong and durable means of inexpensive construction, adapted to be easily operated 15 with a single movement of the hand to open and close a plurality of doors simultaneously, and capable of permitting any of the doors to be disconnected from the operating mechanism, so as to remain either open or 20 closed while the other doors are simultaneously operated.

A further object of the invention is to provide door operating mechanism of this character, which will be entirely concealed 25 from view, and which will indicate positively and clearly the positions of the doors, so that it will be impossible for a door to become disconnected from the operating means and accidentally left open or closed without 30 the knowledge of the person operating the mechanism.

With these and other objects in view, the invention consists in the construction and 35 novel combination of parts hereinafter fully described, illustrated in the accompanying drawings, and pointed out in the claims hereto appended: it being understood that various changes in the form, proportion, size and minor details of construction, within 40 the scope of the claims, may be resorted to without departing from the spirit or sacrificing any of the advantages of the invention.

In the drawings:—Figure 1 is a vertical 45 sectional view of a portion of a jail, equipped with mechanism, constructed in accordance with this invention, for operating and locking jail doors. Fig. 2 is a horizontal sectional view on the line 2—2 50 of Fig. 1. Fig. 3 is a horizontal sectional view on the line 3—3 of Fig. 1. Fig. 4 is a similar view, showing a plurality of door actuating bars connected with the traveler. Fig. 5 is an enlarged detail view of the door locking means. Fig. 6 is a vertical sectional 55 view on the line 6—6 of Fig. 5. Fig. 7 is a detail view of the bottom portion of one of the doors. Fig. 8 is a detail sectional view, illustrating the construction for guiding the bottom of the door. Fig. 9 is a vertical sectional view on the line 9—9 of Fig. 1. Fig. 10 is an enlarged detail sectional view, illustrating the construction of the front groove of the door and the co-acting flanged member. Fig. 11 is a similar view, showing the rear groove of the door and the flanged member which co-acts therewith. Fig. 12 is an enlarged detail view, illustrating the construction for detachably connecting the door actuating means with the traveler. 70

Like numerals of reference designate corresponding parts in all the figures of the drawings.

In the accompanying drawings in which is illustrated the preferred form of the invention, 1 designates a front wall of a row or series of cells 2. Only two of the row or series of cells are illustrated in the drawings, but it will be clear that the row or series may consist of any desired number, 80 and that the door operating and locking mechanism may be constructed to suit the requirements of the jail in which it is to be used. The front wall is provided at each cell with a door opening 3 and is 85 equipped with a slidable door 4, hung from a track 5, which is located within a longitudinal top casing 6 provided at the front with a depending box or extension 7 and containing the mechanism for actuating the 90 doors and for operating the locking means. Each door 4, which is designed to be constructed of sheet metal or other suitable material, is provided at its front edge with inner and outer vertical grooves 8 and 9, 95 and it has corresponding inner and outer vertical grooves 10 and 11 at its rear edge. The front and rear grooves are preferably formed by metallic strips, suitably secured to the inner face of the door, the metallic strip at the rear edge of the door being also angularly bent to provide a projecting transverse flange 12, adapted to conceal a vertical locking bar 13 from the rear when the door is closed. The outer front groove 100 9 receives a vertical flange 14 of a flanged member 15, suitably secured to the front wall at the door opening. The flanged member 15 is arranged in the door opening 105 and is angularly bent at its lower portion 110

to provide an attaching flange 16, which projects in the opposite direction from the flange 14. The attaching flange is secured to the inner face of the front wall of the cell by rivets or other suitable fastening means, which also pierce an outer vertical strip 17. The wall is equipped at the rear side of the door opening with a flanged member 18, having an inner attaching flange 19 and provided at its outer portion with oppositely projecting flanges 20 and 21, extending forwardly and rearwardly and adapted to engage, respectively, the inner front groove 8 when the door is open and the inner rear groove 10 when the door is closed. The front wall of the cell is also equipped with a flanged strip or member 22, having an inner attaching flange and an outer projecting flange, which extends into the rear outer groove 11 of the door when the latter is open. The vertical grooves and the flanges interlock the door with the front wall of the cell and hold the door against outward movement and enable the door to resist lateral pressure in either direction.

The door is provided at the top with an extension 23, projecting upwardly through a slot or opening 24 in the bottom of the longitudinal casing and secured to a horizontal bar or piece 25, forming the body of the carriage or hanger and equipped at its ends with rollers or wheels 26 to run upon the track 5. The track 5 preferably consists of an angle iron secured to the bottom and inner wall of the longitudinal casing 6. The top of the door is also designed to be equipped with flanged strips 26^a, arranged to project beyond the door for covering that portion of the slot or opening 24 unoccupied by the door in order to prevent any article or substance from being introduced into the casing and interfering with the free operation of the mechanism for actuating and locking the doors. The flanged strips 26^a, which are preferably inverted T-shaped in cross section, consist of a vertical web and bottom flanges, the web being arranged in the vertical plane of the door and riveted or otherwise secured to the horizontal bar or piece 25. The door is provided at the bottom with a groove 27 into which projects a fixed guide 28, preferably consisting of spaced lugs having intervening recesses 29 and adapted to permit dirt and other trash to be readily swept past the guide.

Each slidable door is equipped with a door actuating bar 30, consisting of a horizontal body portion, arranged within the top casing and rigidly secured at its rear end 31 to the hanger 25 and provided at its front end with a depending arm 32, arranged in a vertical position and extending into the box 7. The front portion of the door actu-

ating bar is supported in a guide, consisting of spaced upper and lower grooved rollers or wheels 33, mounted on a suitable support 34 and receiving the upper and lower edges of the door actuating bar and permitting the same to slide freely in opening and closing the doors. Each depending arm 32 is provided with a reduced lower end 35, forming a shank and receiving a slidable coupling sleeve 36 retained on the reduced portion or shank 35 by a projection or pin 37, secured to the reduced portion or shank and projecting into a spirally arranged slot 38 of the coupling sleeve. The coupling sleeve forms a housing for a coiled spring 39, engaging the reduced portion or shank of the door actuating bar and the lower closed end of the sleeve and adapted to cause the same, when rotated, to spring downwardly into engagement with a traveler 40. The traveler 40, which is disposed transversely of the top casing 6, is provided with a slot 41, and the lower closed ends of the coupling sleeves of the door actuating bars are reduced to provide projections 42 for engaging in the slot 41, whereby the door actuating bars are coupled or connected to the traveler for enabling a plurality of doors to be operated in unison in opening and closing the same. The spiral slots 38 of the coupling sleeves 36 have sufficiently low pitch to retain the sleeves in an elevated position and to prevent the sleeves from being rotated by the coiled springs 39. By means of the vertically movable coupling sleeves a plurality of door actuating bars may be connected to the traveler for simultaneous operation, and any number or combination of doors of a series may be thus operated while the other doors of such series are left in either an opened or a closed position.

The traveler 40 is provided at its ends with curved arms 43, having terminal journals upon which are mounted rollers or wheels 44, arranged to run on guiding tracks 45. The guiding tracks 45, which project horizontally from the opposite walls of the bar or extension of the top casing, consist of rack bars and are provided at their lower faces with teeth 46, which mesh with gears 47, mounted on a horizontal shaft 48 carried by the traveler. The shaft 48 is arranged in openings 49 of approximately bearing brackets 50, secured to the traveler at the end portions thereof and depending from the same, as clearly shown in Fig. 9 of the drawings. The traveler is equipped with a centrally arranged handle 51, having a bearing opening 52 and constituting a central bearing and support for the shaft 48, and adapted to be grasped by the operator to reciprocate the traveler. The traveler is slidably supported by the tracks, the upper rollers or wheels forming anti-friction devices and the gears causing a uniform

movement of the traveler, so that both ends of the traveler will move at uniform speed and the traveler will be prevented from twisting from its true position, and the 5 slideable doors will be actuated the same distance, whereby a full opening and closing movement of all the doors connected with the traveler may be secured.

Each of the doors is also provided at the 10 top with a projecting portion 53 of a length less than the width of the door, and forming front and rear shoulders 54 and 55, adapted to be engaged by a stud 56 of a bell crank or rocker member 57. The bell crank or rocker 15 member 57, which is approximately triangular, is mounted on a fixed pivot 58, located at the lower portion of the bell crank and at a point intermediate of the lower angles thereof. The pivot 58 is suitably mounted 20 on the inner or rear wall of the box or casing, and the stud 56, which is located in advance of the pivot, is adapted to engage the rear shoulder 55 for locking the top of the casing when the latter is closed, and the 25 said stud 56 is also adapted to engage the front shoulder 54 for locking the top of the door when the latter is open. The bell crank or rocker member is connected at its lower rear angle to the vertically movable 30 locking bar 13 by a suitable pivot 59. The lower end of the locking bar 13 is provided with a horizontally projecting lug 60, adapted to engage front and rear recesses 61 and 62 of the door for locking the bottom thereof, 35 of, when the door is in its opened and closed position. The locking bar is located in rear of the rear flanged member 18, and it extends from the top casing to the bottom of the door and it is actuated by the bell crank 40 or rocker member for carrying the top stud 56 and the lower lug 60 simultaneously into and out of engagement with the top and bottom of the door. As the stud 56 and the lug 60 engage, respectively, the top shoulders 45 and the lower recesses of the door, the latter will have to be either in an open or closed position in order to operate the locking mechanism, which is adapted to secure the door either in its open or closed position. 50 The bell cranks or rocker members are connected at their upper angles by suitable pivots 63 to the rear ends of the horizontal connecting bars 64, extending forwardly to an operating or master lever 65, fulcrumed 55 at an intermediate point on a suitable pivot 66 and provided with a plurality of upper slots 67, adapted to receive the front ends of the connecting bars 64. The connecting bars 64 are provided at their lower edges with 60 notches 68, adapted to be engaged by bolts 69 of catches, mounted on the operating lever 65 for detachably coupling the front ends of the connecting bars to the operating lever. Each bolt 69 is actuated by a spring 65 and is connected at its lower end with a lever

79, pivoted at its inner end to a flange 80 of the master or operating lever 65 by a pin 81, or other suitable fastening device and extending through a lower longitudinal slot 82 in the said master or operating lever 65. 70 The bolt actuating lever, which is provided with a grip or handle, is adapted to be swung upwardly and downwardly in the slot 82. The slot 82 is provided at its lower end with a lateral branch or recess, which is 75 adapted to receive the lever 79 for holding the bolt 69 out of engagement with the notch 68 of the connecting bar 64.

Only two slots are shown in the operating or master lever in the accompanying drawings, but it will be understood that the number of slots will correspond with the number of locking means to be operated. The master or operating lever is arranged in an inclined position when the locking means is in 80 engagement with the door or doors, and it is secured in such position by a spring actuated detent 71, mounted on the operating or master lever and arranged to engage a toothed or notched bar or segment 72, suitably secured to the rear wall of the box or extension 7 of the top casing. The spring actuated dog or detent is operated by a latch lever in the ordinary manner, and it is adapted to lock the lever in its adjustment. 85 The box or casing may be equipped with a suitable door, or the operating means may be otherwise made inaccessible to prisoners and other unauthorized persons. As the door actuating bars and the connecting bars 90 extend directly from the actuating means to the doors and the bell crank or rocker members, there is no lost motion and a simple construction, not liable to get out of operation is provided. The position of the parts 95 within the box or extension will afford infallible means for indicating the positions of the various doors in the series, so that there is no liability of any one of the doors of a series being accidentally left in the wrong 100 position if the operator is careful. The locking mechanism of any of the doors of the series may be disconnected from the operating lever, so that trustees or other persons may open and close the disconnected 105 doors at will.

No claim is made in the present application to the locking mechanism.

Having thus fully described my invention, what I claim as new and desire to secure by 120 Letters Patent, is:—

1. In mechanism of the class described, the combination with a plurality of sliding doors, a horizontal traveler, means for slidably mounting the same, horizontal door actuating bars connected with the doors and having depending arms terminating above the plane of the traveler, and devices carried by the depending arms and movable into and out of the plane of the traveler and pro- 125 130

- vided with means for engaging the same, whereby one or more door actuating bars may be connected with the traveler.
2. In mechanism of the class described, the combination of a plurality of slidable doors, spaced rack bars, a slidable traveler guided at spaced points by the rack bars, pinions carried by the traveler and meshing with the rack bars, and means for detachably connecting the doors with the traveler.
3. In mechanism of the class described, the combination of a plurality of slidable doors, spaced rack bars, a traveler having wheels arranged to run on the rack bars, a shaft mounted on the traveler and located beneath the rack bars, pinions fixed to the shaft and meshing with the teeth of the rack bars, and means for connecting the doors with the traveler.
4. In mechanism of the class described, the combination of a plurality of doors, spaced rack bars, a traveler guided by the rack bars and provided between the same with an operating handle, connected gears mounted on the traveler and meshing with the rack bars, and means for connecting the doors with the traveler.
5. In mechanism of the class described, the combination of a plurality of doors, actuating bars connected with the doors, a slidable traveler having a slot, and means mounted on the door actuating bars for detachably engaging the slot of the traveler to connect the doors therewith.
6. In mechanism of the class described, the combination of a plurality of slidable doors, door actuating bars connected at one end with the upper portions of the doors and provided at the other end with depending arms, a slidable traveler operating in a plane beneath the depending arms, and coupling means for detachably connecting the arms of the door actuating bars with the slidable traveler.
7. In mechanism of the class described, the combination of a plurality of slidable doors, door actuating bars connected at one end with the upper portions of the doors and provided at the other end with depending arms, a slidable traveler operating in a plane beneath the depending arms, and coupling sleeves mounted on the arms and de-
- pending from the same and provided with means for engaging the traveler and movable into and out of engagement with the same.
8. In mechanism of the class described, the combination of a plurality of slidable doors, door actuating bars connected at one end with the upper portions of the doors and provided at the other end with depending arms, a slidable traveler operating in a plane beneath the depending arms, coupling sleeves having spiral slots and arranged on the arms and provided at their lower ends with means for engaging the traveler, projections carried by the arms and extending into the spiral slots, and springs engaging the sleeves and the arms for urging the former downwardly and for maintaining the sleeves in engagement with the traveler.
9. In mechanism of the class described, the combination of a plurality of slidable doors, horizontal door actuating bars connected at one end with the doors and provided at the other end with vertical arms, slidable sleeves mounted on the arms and having reduced outer terminal portions, a slidable traveler having a slot arranged to receive the reduced terminal portions of the sleeves, and means for maintaining the sleeves in engagement with the traveler and for holding the sleeves out of such engagement.
10. In mechanism of the class described, the combination of a top longitudinal casing having a depending box or extension and provided with slots, slidable doors extending through the slots into the top casing, horizontal door actuating bars connected at one end with the doors and provided at the other end with arms depending into the box or casing, an operating device, and means for connecting the arms with the operating device.

In testimony that I claim the foregoing as my own, I have hereto affixed my signature in the presence of two witnesses.

DAVID FRANKLIN YOUNGBLOOD.
